UNITED STATES PATENT OFFICE.

ANGELO CASCIA, OF NEW YORK, N. Y.

MOUTHPIECE FOR CIGARS.

1,315,209.

Specification of Letters Patent. Patented Sept. 9, 1919.

Application filed October 24, 1918. Serial No. 259,587.

To all whom it may concern:

Be it known that I, ANGELO CASCIA, a citizen of the United States, and resident of New York, in the county of New York and State of New York, have invented certain new and useful Improvements in Mouthpieces for Cigars, of which the following is a specification.

This invention relates to cigar mouth pieces and its object is to provide the said cigar with a permanent tip of flexible and porous substance to prevent the end of the cigar from becoming soggy and frayed before the cigar is consumed and to provide the piece with a dissolving flavoring or medicinal preparation as will be more fully described in the following specification, set forth in the appended claims and illustrated in the accompanying drawings, wherein:

20 Figure 1 is a side elevation of a cigar with the improved mouth piece applied thereto.

Fig. 2 is a side view of the cigar with the mouth piece in section.

25 Fig. 3 is a plan view of a modified mouth piece.

Fig. 4 is a sectional view of the mouth piece detached.

Fig. 5 is an end view of the mouth piece.

The improved mouth piece is adapted to be permanently secured to the tip of the cigar and pasted or immovably fitted thereon, becoming a part and parcel of the cigar when sold and to be thrown away with the stump. The piece is therefore to be made of cheap material which will not add much to the cost of the cigar and be sufficiently soft or yielding so as not to be hard and objectionable to the teeth while holding the cigar.

40 Non-inflammable material is preferable but papier-mâché, pulverized cork, vulcanized fiber or wood are suitable for the purpose and flavors may be given same or granulated tobacco may be applied to the 45 outside of the mouth piece or mixed with the composition during its preparation to simulate the tobacco or cigar taste without the danger of undesirable soggy conditions.

The mouth piece consists of the cup-shaped cap 8 with a perforation 9 and a bead 10 at its outer end, and while the front edge of the cap is annular the bead and the neck 11 thereto are preferably oval and depressed vertically for security in grasping the de-

vice by the teeth while smoking, or the rear 55 end of the cap may be convex so as to afford greater depth within the cup for the end of the cigar and to insure its being securely attached thereto as shown in Fig. 3. In the latter case the end 12 is broadened and flattened.

To secure the mouth piece to the cigar 13 its interior or the tip of the cigar is provided with suitable paste or cement, preferably waterproof cement, which will 65 resist heat or moisture, and this cement may also insulate the mouth piece so that the entire cigar may be consumed without inconveniencing the smoker.

The device will enable the consumer to 70 smoke the entire cigar if high priced and thus amply compensate for the cost of the mouth piece in addition to the comfort afforded.

In the construction of the device from material which is cheap and easily manipulated, antiseptic preparations, powdered tobacco, medicine or flavoring preparations may be mixed with the composition and impart beneficial effects or results to the 80 smoker.

The flavoring of medicinal material may be mixed with the composition of the mouth piece when being prepared and may be in the form of powder or of liquid which will 85 leave a dissolving sediment.

It is obvious that other modifications may be resorted to in the construction of the device without departing from the essential features above described or from the scope 90 of the appended claims.

The device may be merged flush with the cigar as shown in Fig. 1 and instead of using a cement, a staple, tack or loop of thread 14, as in Fig. 3, may be used to secure the 95 mouth piece.

What I claim as new is:

1. In a mouth piece for cigars, the combination of a cap of porous composition conforming with and adapted to envelop the 100 end of a cigar and adapted to be permanently affixed to the end of a cigar and containing as an ingredient a substance soluble to heat and moisture with the rearward perforation for the passage of smoke, and 105 means for affixing the mouth piece to a cigar.

2. In a mouth piece for cigars, the com-

bination of a cap of a porous compound one of whose components is a substance adapted to dissolve by moisture when held in the mouth of the smoker and conforming with 5 the shape of the rear end of the cigar and adapted to be affixed thereto, means for affixing the mouth piece or cap to the cigar, and

a flattened end and a bead at the extremity of the cap.

Signed at New York, in the county of 10 New York and State of New York this 24th day of September A. D. 1918.

ANGELO CASCIÀ.
